UNITED STATES PATENT OFFICE.

JOHN D. EDWARDS, OF DECATUR, INDIANA.

REFINING OILS.

SPECIFICATION forming part of Letters Patent No. 449,213, dated March 31, 1891.

Application filed August 19, 1890. Serial No. 362,425. (No model.)

To all whom it may concern:

Be it known that I, JOHN D. EDWARDS, a citizen of the United States, residing at Decatur, in the county of Adams and State of Indiana, have invented a new and useful Oil-Purifier, of which the following is a specification.

This invention relates to the treatment of oils, and more especially to the refining or cleansing thereof by passing the same through water or through some other liquid of greater specific gravity than the oil.

The object of the invention is to effect this cleansing of the oil in a very economical and yet rapid manner; and to this end the invention consists of a device for the purpose, preferably constructed in the manner hereinafter more fully described, and as illustrated in the drawings, in which—

20 Figure 1 is a perspective view of my refining apparatus complete. Fig. 2 is a plan view of the reservoir removed from the tank. Fig. 3 is a central vertical section of the parts assembled, showing the tank partially filled 25 with water and oil passing from the reservoir through the water. Fig. 4 is an enlarged section on the line 4-4 of Fig. 3.

Referring to the said drawings, the letter T designates a tank, and the letter R a reservoir adapted to fit into the upper end of the tank, and closed in turn at its upper end by the removable cover C. All these parts are of tin, galvanized iron, or other suitable material possessing the necessary strength. The 35 tank T is preferably cylindrical in shape, and the reservoir R the same, except that in one side (or more, as in Fig. 2) is formed a chamber, the bottom B of the reservoir being continued, so as to close the upper end of the 40 tank, but the wall forming the side of the reservoir being preferably curved inwardly, as shown at W in Fig. 1. The cover C may have a knob or other device K, and the tank T may have handles H for obvious use.

45 Through the curved wall W of the reservoir passes a drip-cock 3, whose inner end is covered by a wire screen 2, and in the bottom B of the reservoir is formed a hole beneath said drip-cock, which hole is covered 50 with a fine wire screen 4. Depending from

said bottom B is a tube 5, whose upper end surrounds said fine screen, and on this tube is secured a pair of deflectors, which are of funnel shape. The lowermost deflector 6 tapers upwardly, and preferably has holes 9 55 through its body, and the uppermost deflector 7 tapers downwardly and is preferably without the holes 9. The tank T is provided with a cock 10 for drawing off water, and at the point indicated with a cock 11 for drawing off 60 the refined oil.

The operation of the device is as follows: The reservoir R being filled with oil and the cock 3 opened, so as to permit a fine flow therethrough, (this flow depending upon the 65 density of the oil,) the latter passes first through the coarse screen 2, then through the drip-cock 3 upon and through the fine screen, down through the tube 5, and out the lower end thereof. The tank T has previously been filled with water or with some other refining liquid up to about the line 8, which is below the cock 11, and, as the oil issues from the lower end of the tube 5, it passes first upwardly through the holes 9 in the lowermost deflector 6, rising through the water, than which it is of less specific gravity, until it strikes the uppermost deflector 7, whereby it is caused to pass outwardly away from the tube 5, and it finally floats upon the water, as 70 shown. The oil can be drawn off through the cock 11 at any time desired. The water or other refining agent can be drawn off through the cock 10 after it has become foul or whenever else desired. The reservoir and tank 75 80 can be filled from the top in any preferred manner. The drip-cock 3 can be set so as to drip faster or slower, or even to permit a small stream to flow, if desired, and the reservoir R can be provided with several drip-cocks 3 and tubes 5, each arranged upon the bottom B and within an inwardly-curved portion of the side wall W, the same as above described, all without departing from the spirit 85 90 of my invention.

What is claimed as new is—

The herein-described oil-refiner, the same comprising a tank T, adapted to be partially filled with water, an oil cock 11 therein above the water-level 8, a reservoir R, having its 100

bottom B closing the top of the tank and provided with the curved side W, a tube 5, leading from the bottom B downwardly within said tank to a point below the water-level, the 5 drip-cock 3, leading from the reservoir to the upper end of the tube, a conical deflector 6 upon said tube near its lower end, provided with a number of holes 9, and an upwardly-flaring funnel-shaped deflector 7 upon said 10 tube above said perforated deflector, but be-

low the water-level, all as and for the purpose hereinbefore set forth.

In testimony that I claim the foregoing as my own I have hereto affixed my signature in presence of two witnesses.

JOHN D. EDWARDS.

Witnesses:

W. H. NIBLICK,
C. S. NIBLICK.
